UNITED STATES PATENT OFFICE.

JOHN E. OSMER, OF OWOSSO, MICHIGAN, ASSIGNOR OF ONE-HALF TO FREDERICK H. SMITH, OF COLUMBUS, OHIO.

EXHAUST MECHANISM FOR LOCOMOTIVES.

Application filed July 19, 1920. Serial No. 397,359.

To all whom it may concern:

Be it known that I, JOHN E. OSMER, a citizen of the United States, residing at Owosso, in the county of Shiawassee and State of Michigan, have invented certain new and useful Improvements in Exhaust Mechanism for Locomotives, of which the following is a specification.

The invention relates to locomotives and is directed more particularly to means for effecting the closure of the exhaust nozzle for various reasons, chief among which is that of preventing, when the flow of steam is cut off, the passage of smoke, soot, cinders, and the like from the smoke box of the locomotive through the exhaust passage into the cylinders. In my copending application, Serial No. 493,351, filed August 18, 1921, I have illustrated, described and claimed valve means designed to accomplish this and allied functions.

The object of the present invention is to provide a controlling mechanism for valve means of the character referred to, which will accomplish automatically the efficient operation of said valve means.

More specifically, an important object of the invention is to provide means for controlling the flow of pressure-fluid to said valve means to actuate the same, and the exhaust of pressure-fluid from the valve means at the proper time to enable the valve means to close the passageway through the exhaust passage.

A further object of the invention is to provide controlling mechanism of the character indicated by means of which the pressure-fluid employed for actuating the valve may be changed at will from one kind to another as, for example, from steam to air under pressure or vice versa.

A further object of the invention is to provide means for controlling the flow of pressure-fluid, such as compressed air, through the exhaust valve, which is automatically governed by the presence of steam under pressure in the engine cylinders or other convenient part of the locomotive.

As set forth in my said copending application, another function of said valve means in the exhaust nozzle is that of converting the engine cylinders into air pumps when the control lever of the locomotive is thrown into the reverse position with reference to the direction of travel of the locomotive, for

the purpose of replenishing from time to time the supply of air in the air reservoir.

A further object of the invention is to provide controlling mechanism by means of which the engine cylinders may be connected at will with the air reservoir for this purpose.

Other and ancillary objects of the invention such, for example, as the advantageous construction and arrangement of the parts, will be apparent as the description proceeds. It is to be understood, however, that while the invention is herein illustrated and described with considerable particularity, it should not, in the interpretation of the appended claims, be limited to the particular embodiment selected for illustration, for I recognize that various changes and modifications may be made without departing from the spirit and scope of the invention.

In the accompanying drawings, Figure 1 is a fragmentary vertical section through the smoke box of the locomotive, the exhaust nozzle and associated parts being shown in elevation. Fig. 2 is a fragmentary vertical central sectional view through the exhaust nozzle and its controlling valve. Fig. 2^a is a fragmentary vertical sectional view through the lower portion of the exhaust nozzle looking in a direction at right angles to that shown in Fig. 2. Fig. 2^b is a horizontal section taken on line 2^b—2^b of Fig. 2. Fig. 3 is a vertical central sectional view through the controlling mechanism, the pipe connections and the controlling cock therefor being shown in elevation. Fig. 3^a is a detail view of the air valve for the controlling mechanism. Fig. 4 is a view in elevation of the controlling cock detached. Figs. 5 to 8 are sectional views somewhat diagrammatic in character through the controlling cock and its pipe connections illustrating respectively the various positions of the parts under different circumstances. Thus, Fig. 5 illustrates the cock in position for the operation of the exhaust valve by air under pressure, whose admission is automatically controlled by steam pressure in the engine cylinders;

Fig. 6, the cock in position for the operation of the exhaust valve by steam alone; Fig. 7, the position of the cock for the replenishment of the air reservoir by the operation of the engine cylinders as air pumps; and Fig. 8, the cock in position for the operation of the exhaust valve by air alone.

Referring first to Figure 1, 10 designates the forward end of a locomotive boiler providing therein the usual smoke box from which leads a stack 11. 12 designates one of the engine cylinders, and 13 designates one of the steam pipes, leading to the cylinder 12. The flow of steam from the boiler to the cylinder 12 by way of the pipe 13 is, of course, controlled in the usual manner 10 by suitable throttle mechanism (not shown); and the steam exhausting from the cylinders is conducted to an exhaust nozzle 14 which is adapted to discharge at its upper end into the stack 11.

Referring now to Fig. 2, the exhaust nozzle 11 is cylindrical in form, being secured to the locomotive saddle, indicated generally at 15 (Fig. 1), by suitable bolts extending through the flanged lower end of 20 the nozzle, the lower wall of the smoke box, and into the saddle. In the lower portion of the nozzle is provided a central partition or web 16 dividing the nozzle into two passages communicating respectively with the 25 cylinders on opposite sides of the locomotive in the usual way and terminating in a single passage in the upper portion of the nozzle. At its upper end the nozzle has a cap portion 17 detachably secured upon the 30 lower or base portion by means of bolts 18, the cap 17 being restricted in size at its upper end.

At the upper end of the lower or base portion of the nozzle is provided a valve 19 35 for controlling the passage of air and foreign substances such as soot and cinders through the nozzle. Preferably, said valve consists of a main or central portion 19^a which is in the form of an inverted cone the 40 upper peripheral edges of which are adapted to seat as at 20 upon the upper annular edge of the lower or base portion of the nozzle. For the purpose of guiding the valve in its up and down movements, a plurality of wings 19^b extend radially from the 45 central conical portion 19^a and slidably engage with the inner surface of the upper end of the base portion 14 of the nozzle. Recesses 21 may be provided in the wing 19^b 50 to prevent unequal steam pressure on the valve portion 19^a.

In order that the valve may be actuated by fluid-pressure, I provide within the upper end of the conical portion 19^a a chamber 22 closed at its upper end by a plate 23 secured upon the upper end of the valve; and into this chamber pressure-fluid is admitted through a tubular stem 24 anchored at its lower end in the web 16, and communicating with a passage 25 connected with the source of supply in a manner which will be hereinafter apparent. To rigidly secure the stem 24 in the web 16, a set-screw 24^a entered through the web from the exterior of the nozzle, may be employed. The

stem 24 is entered loosely through an aperture 26 in the lower conical portion of the valve 19, so that the valve is free to move with reference to the stem 24. At its upper end the stem 24 is enlarged to provide a 70 head constituting a piston 27 fitting neatly within the chamber 22. This construction is provided in order that any tendency of the valve to flutter because of fluctuations in the pressure of the exhaust steam shall 75 be prevented, the piston and chamber constituting a dash-pot as will be readily apparent. Preferably the aperture 26 is made of such size as to provide a slight clearance 80 around the stem 24 so as to permit of the escape of air from the chamber 22 below the piston 27 in the upward movement of the valve.

Pressure-fluid-actuated means is employed to operate the valve 19; and while it is to be understood that any suitable or preferred form of pressure-fluid desired may be employed, I prefer the use of compressed air, the flow of which is controlled by steam under pressure in the engine cylinders or other convenient part of the locomotive. To this end I provide a reservoir 28 for the storage of air under pressure, from which the air is conducted to the exhaust nozzle by suitable pipe connections 29 and 29^a under the control of a cock 30 and having interposed therein a controlling device 31. The pipe 29^a passes through the lower wall of the smoke-box forwardly of the nozzle and thence rearwardly to the nozzle (dotted lines Fig. 1). The cock 30 is operatively associated with the device 31 so as to govern the flow of air to the device for passage therethrough as well as for the purpose of operating the valve means thereof. To this end the cock, as shown in Figs. 4 to 8, is of the three-way type. Herein the cock is provided with a suitable handle 32 by means of which it may be manually operated as desired. Obviously, however, suitable means may be employed for facilitating the operation of this cock conveniently by the engineer.

The device 31 (Fig. 3) comprises a casing 33 of sectional construction and valve means therein for controlling the flow of pressure-fluid therethrough in one direction to the exhaust valve and in the other direction from the exhaust valve to the atmosphere. Thus I have shown the casing as comprising a lower section 34 and an upper section 34^a removably secured together by means of a spanner nut 35. The lower section has at its lower end an inlet passage 36 adapted for communication with a source of steam under pressure. Herein the lower end of the section 34, has a threaded nipple 37 adapted to be entered within an aperture in the wall of the steam chest, at a convenient point for the admission of steam to the controlling device. 115 120 125 130

Between the two sections 34 and 34^a of the casing is formed a chamber 38 having therein a piston 39 which is exposed at its lower end to steam pressure introduced by way of the passage 36. Operatively associated with said piston 39 is a cylindrical valve member 40 operatively mounted in the upper section 34^a of the casing and adapted to control the flow of pressure-fluid therethrough in opposite directions as above set forth. Said valve member 40, to this end, is mounted to fit neatly within a cylindrical bore 41 communicating with an outlet port 42 with which is connected the pipe section 29^a leading to the exhaust nozzle. At a point above the valve member 40 the casing is provided with an inlet port 43 communicating by way of a pipe 44 with one end of the cock 30, the opposite end of said cock being connected with the pipe section 29 leading from the air reservoir 28. At its inner end said port 43 communicates with a chamber 45 closed at its upper end by a plug 46 between which and the valve member 40 bears a coiled compression spring 47. At its upper end the valve member 40 has a head 48 of relatively small area and adapted to rest upon an annular seat 49 provided at the lower end of the chamber 45, and it will be seen that the spring 47 tends to maintain the valve-head 48 upon its seat. When, however, steam under pressure is present in the engine cylinder, it will be apparent that it acts through the larger pressure area provided by the piston 39 to raise the valve 40, whereupon the flow of pressure-fluid from the port 43 through the chamber 45 and to the port 42 is permitted. For this purpose, the valve member 40 is provided in its periphery with a longitudinal groove 50 and a circumferential groove 51 interrupting and communicating with the longitudinal groove. The last mentioned groove preferably extends from the lower end of the valve member 40 to the head 48, so that when the latter is lifted from its seat, pressure-fluid enters the upper end of the groove 50 and thence flows by way of the circumferential groove 51 to the port 42 from whence it flows through the pipe section 29^a to the exhaust nozzle.

Normally, with the valve member 40 maintained by the spring 47 in position to close the passageway from the port 43 to the port 42, the longitudinal groove 50 in the valve member opens into the chamber 38 above the piston 39. Leading from this chamber is a leakage or exhaust port 52. Thus it will be apparent that when the pressure of steam upon the lower end of the piston 39 subsides by reason of the throttling of the steam by the engineer, the air which has previously been admitted to the chamber 22 of the valve 19 by way of the pipe section 29^a will escape to the atmosphere through the groove 50, chamber 38 and port 52. In order to seal the lower end of the groove 50 when the valve member 40 is raised by steam pressure to permit of the flow of pressure-fluid to the exhaust nozzle, the upper end of the piston 39 has a disk 53 adapted to enter a cavity 54 in the upper wall of the chamber 38 around the bore 41 to close the lower end of the latter. If desired, a diaphragm 55 is provided in the chamber 38 being secured at its center between the disk 53 and the piston, and its peripheral edge between the upper section 34^a of the casing and an annular member 56 resting upon the upper end of the lower section 34, the parts being secured in position by the spanner nut 35. This diaphragm, it will be apparent, provides an absolute seal preventing the passage of steam past the piston 39 into the upper portion of the casing. Obviously, however, other forms of sealing means may be employed. The member 56 provides a central annular ring or collar 57 which serves as a guide for the piston 39.

The lower end of the piston 39 is of a restricted diameter, and fits neatly in a chamber 58, and bearing upon said restricted lower end of the piston is a coiled compression spring 59 engaging at its opposite end with a check valve 60 having radially extending wings 61 slidably engaging with the inner surface of the passage 36. The spring 59 is of less strength than the spring 47 which controls the air-valve, and serves to maintain the valve 60 normally seated at the upper end of said passage 36, so that while it permits of the passage of steam upwardly against the piston 39, it serves to prevent the return passage of the steam into the engine cylinder through the passage 36. Leading from the chamber 58 in the lower section 34 of the casing 33 is a port 62 from which leads a pipe 62^a the opposite end of which communicates with the cock 30. Communication may thus be established at will, by manipulating the handle 32 of the cock 30, between the chamber 58, communicating with the source of steam supply, and either the air pipe 29 or the casing of the controlling device for passage therethrough to the exhaust valve.

The operation is as follows: Assuming that it is desired to effect the automatic operation of the valve 19 in the exhaust nozzle by employing a pressure-fluid such as compressed air for actuating the valve, and controlling the flow of the air by steam pressure taken from the engine cylinder or other source; the cock 30 is operated to the position shown in Fig. 5 in which communication is established between the reservoir 28 and the upper section 34^a of the casing of the controlling device, and in which steam pressure is admitted through the passage 36 at the lower end of the casing to the underside of the piston 39. The piston 39 is thus

actuated and with it the valve member 40 is raised to lift the valve head 48 from off its seat 49 and thus permit the flow of air from the inlet port 43 to the outlet port 42 by way of the upper portion of the longitudinal groove 50 and the circumferential groove 51. The lower end of the groove 50 is at this time closed by means of the disk 53 engaging in the cavity 54 in the upper wall of the chamber 38. Pressure-fluid therefore passes through the cock 30 to the controlling device 31 and by way of the pipe section 29^a to the exhaust nozzle where it acts upon the piston 27 in the chamber 22 of the valve 19 to raise the latter from off its seat 20.

If desired, exhaust steam, or air pressure properly controlled, may be employed to merely assist the exhaust steam passing through the nozzle in actuating the valve. 20 In the event that it is desired to employ exhaust steam, the same may be admitted through the passage 25^a (Fig. 2) extending downwardly through the web 16 and communicating with one of the exhaust passages 25 by way of a groove 25^b, thus avoiding the use of any pipe connections. For this operation the cock 30 is manipulated to the position shown in Fig. 7, to cut off the flow of live steam or compressed air, and in the operation 30 of the engine, steam passing through the nozzle is admitted to the chamber 22 of the valve to raise it. If the pressure may be such that it is insufficient in itself to raise the valve member from its seat 20, but sufficient to coact with a comparatively slight force of exhaust steam passing through the nozzle to overcome the weight of the valve. It will thus be apparent that in this event the exhaust valve "floats" upon the exhausted steam as the latter discharges into the cap 17, and the result is that a restricted opening is provided between the upper periphery of the valve 19 and the seat 20 which serves to effect a wire-drawing of the steam, thus 40 increasing the velocity thereof so as to produce an effective draft upon the fire in the fire-box even though the force of the exhaust steam is relatively low.

To prevent the escape of air or live steam, 50 when either of these are employed, the passage 25^a may be provided at its lower end with a suitable check valve 25^c.

If it should be desired to actuate the valve 19 by the use of steam pressure alone, the 55 cock 30 is operated to the position shown in Fig. 6 in which communication with the air reservoir is cut off and is established with the passageway leading from the lower end of the casing of the controlling device, through 60 the pipe 62^a. Steam is thus admitted into the upper portion of the casing through the pipe 62^a, the cock 30 and the pipe 44, and the pressure thereof in the chamber 58, before passing to the pipe 62^a, upon the under side 65 of the piston 39 lifts the valve member 40

to carry its head 48 off from its seat 49, thus permitting the steam to flow through the upper portion of the casing by way of the grooves 50 and 51 and through pipe connection 29^a to the valve chamber 22 in the 70 exhaust valve. When the steam pressure subsides, the piston 39 descends to permit the escape of pressure from the chamber 22 in the valve 19 through the pipe section 29^a, the grooves 51 and 50, into the upper portion 75 of the chamber 38 above the diaphragm therein, from whence it escapes to the atmosphere by way of the port 52.

Should it be desired to actuate the valve 19 by the use of air pressure alone, the cock 80 is manipulated to the position shown in Fig. 8. The operation is substantially similar to that wherein air and steam are employed (Fig. 5) except that a quantity of air is shunted through the pipe 62^a to the chamber 58 so as to act upon the piston 39 for the purpose of lifting the air valve from its seat and permitting the flow of air through the casing to the exhaust valve. It will be understood, of course, that the check valve 60 actuated by the spring 59, prevents the air from flowing downwardly into the engine cylinders through the passage 36. When the flow of air from the reservoir is cut off by the manipulation of the cock into a position 90 such as shown in Fig. 6, the piston 39 and valve 40 move to their normal position in which the escape of pressure-fluid by way of the groove 50 and port 52 is permitted.

When the locomotive is coasting or drawn dead in the train, it may be desired to restore the supply of compressed air to the air reservoir 28. This is accomplished by manipulating the cock 30 to the position shown in Fig. 7 wherein communication with the upper portion of the casing 33 is cut off and is established between the pipe section 29 and the pipe 62^a. In this operation of restoring the supply of air, the control lever of the locomotive is thrown into a position opposite to that of the travel of the locomotive, and the air is drawn through suitable valves in the cylinders and pumped into the reservoir by way of the passage 36 and chamber 58 in the lower portion of the casing of the control device, the pipe 62^a, cock 30, and the pipe section 29. The valve 60 at the upper end of the passage 36 at the lower end of the casing serves in this operation as a check valve preventing the return flow of air to the cylinder.

An important function of the valve 19 in closing the passageway through the exhaust nozzle is that, when the locomotive is being hauled dead in a train or is coasting, the vacuum created in the engine cylinders by the operation of the pistons serves to retard the movement of the locomotive, having a braking effect transmitted to the wheels by the pistons and connected parts. Moreover, by reason of the resistance to the movement 115 120 125 130

of the pistons when the engine is operating idly, the knocking or pounding of the parts, which is commonly experienced, is wholly eliminated.

- 5 It will be seen that I have provided means of a very practical character for controlling the operation of the locomotive both while operating under its own power and while operating idly in coasting or being hauled 70
10 dead in a train. The construction and arrangement of parts is of a very practical character, the operation may be entirely automatic, and a high efficiency of control is made possible.

15 I claim as my invention:—

1. In combination with a locomotive exhaust passage, a source of air supply and a source of steam supply, a valve for said passage adapted to be actuated by pressure fluid, and controlling mechanism for said valve comprising a casing having an inlet communicating with the air supply, an inlet communicating with the steam supply, an outlet connected with said passage for 80
20 supplying pressure fluid to said valve to actuate it, and an exhaust port, and means operable in said casing by pressure at the steam inlet to control communication between the air inlet and said outlet and between said outlet and said exhaust port.
2. In a locomotive, the combination of an exhaust passage, a valve for said passage, and means for actuating said valve comprising a chamber, a piston in said chamber, 85
30 means for conducting pressure fluid to said chamber, and a device interposed in the last mentioned means for controlling the flow of pressure fluid to and from said chamber, said device comprising a casing having an inlet, an outlet and an exhaust port, and pressure fluid actuated valve means adapted in one position to establish communication between said inlet and said outlet and in another position to establish communication 90
40 between said outlet and said exhaust port.

3. In a locomotive, the combination of an exhaust passage, a valve for said passage, pressure-fluid-actuated means for operating said valve, means for conducting pressure-fluid to the last mentioned means and having a controlling device therefor comprising a casing having an inlet communicating with a source of pressure-fluid supply, an outlet communicating with said actuating means, and an exhaust port, and pressure fluid actuated valve means in the casing operable to control the flow of pressure fluid from said inlet to the outlet and from the outlet to the exhaust port.

4. In a locomotive the combination of an exhaust passage, a valve for said passage, pressure-fluid-actuated means for operating said valve, means for conducting pressure fluid to the last mentioned means and having a controlling device therefor comprising a

casing having an inlet communicating with a source of pressure-fluid supply, an outlet communicating with said actuating means, and an exhaust port, and valve means in the casing operable to control the flow of pressure fluid from said inlet to the outlet and from the outlet to the exhaust port, the last mentioned means comprising a piston and means for admitting pressure fluid to said piston to actuate it. 75

5. In a locomotive, the combination with an exhaust passage and a valve therefor, pressure-fluid-actuated means for operating said valve including a controlling device comprising a casing having an inlet communicating with a source of pressure fluid supply, an outlet communicating with said actuating means, and an exhaust port, and a spring controlled pressure fluid actuated valve operable to establish communication either between said inlet and said outlet or between said outlet and the exhaust port. 80

6. In a locomotive, the combination with an exhaust passage and a valve therefor, pressure-fluid-actuated means for operating said valve including a controlling device comprising a casing having an inlet communicating with a source of pressure fluid supply, an outlet communicating with said actuating means, and an exhaust port, and a pressure-fluid-actuated valve operable to establish communication either between said inlet and said outlet or between said outlet and said exhaust port. 85

7. In a locomotive, the combination with an exhaust passage and a valve therefor, pressure-fluid-actuated means for operating said valve including a controlling device comprising a casing having an inlet communicating with a source of pressure-fluid supply, an outlet communicating with said actuating means, and an exhaust port, a valve in said casing normally establishing communication between said outlet and said exhaust port, a pressure-responsive member adapted to actuate said valve, and means for conducting fluid under pressure to said member to actuate it whereby to establish communication between said inlet and said outlet. 100

8. In a locomotive, the combination with an exhaust passage and a valve therefor, pressure-fluid-actuated means for operating said valve including a controlling device comprising a casing having an inlet communicating with a source of pressure-fluid supply, an outlet communicating with said actuating means, and an exhaust port, a valve in said casing normally establishing communication between said outlet and said exhaust port, a pressure-responsive member adapted to actuate said valve, and means for conducting fluid under pressure to said member to actuate it whereby to establish communication between said inlet and said outlet. 105

- let, said casing having a spring tending to hold the valve in position to cut off communication between said inlet and said outlet.
5. 9. In a locomotive, the combination with an exhaust passage and a valve therefor, pressure-fluid-actuated means for operating said valve including a controlling device comprising a casing having an inlet communicating with a source of pressure-fluid supply, an outlet communicating with said actuating means, and an exhaust port, a valve in said casing normally establishing communication between said outlet and said 10 exhaust port, a pressure-responsive member adapted to actuate said valve, means for conducting fluid under pressure to said member to actuate it whereby to establish communication between said inlet and said outlet, said 15 pressure-responsive member being in the form of a piston guided in its movements by the casing, and means associated with said piston for preventing the passage of pressure-fluid past it to said exhaust port.
20. 10. In a locomotive, the combination with an exhaust passage and a valve therefor, pressure-fluid-actuated means for operating said valve including a controlling device comprising a casing having an inlet communicating with a source of pressure-fluid supply, an outlet communicating with said actuating means, and an exhaust port, a valve in said casing normally establishing communication between said outlet and said 25 exhaust port, a pressure-responsive member adapted to actuate said valve, means for conducting fluid under pressure to said member to actuate it whereby to establish communication between said inlet and said outlet, said 30 pressure-responsive member being in the form of a piston guided in its movements by the casing, and means associated with said piston for preventing the passage of pressure-fluid past it to the 35 exhaust port when communication between the inlet and said outlet is established.
35. 11. In a locomotive, the combination of an exhaust passage, a valve for said passage, pressure-fluid-actuated means for operating said valve, and controlling mechanism for the last mentioned means including a device comprising a casing having an inlet, an outlet and an exhaust port, valve means in said casing, a pressure-responsive member operatively associated with said valve means, and means for conducting fluid under pressure to said pressure-responsive member to actuate it and said valve means, said valve means being adapted in one position to establish communication either between said inlet and said outlet and in another position between said outlet and said exhaust port.
40. 12. In a locomotive having an exhaust passage and a valve member therefor, pressure-fluid actuated means operable to actuate said valve member, and a device for controlling the flow of pressure fluid to and from said means, said device being operable automatically upon the admission of steam 70 to the engine to operate it.
45. 13. In a locomotive, the combination with an exhaust passage and a valve therefor, pressure-fluid-actuated means for operating said valve including controlling mechanism comprising a casing having an inlet, an outlet and an exhaust port, valve means in said casing for controlling communication between said inlet and outlet and between said outlet and said port, a pressure-responsive member operatively associated with said valve means, means for conducting steam under pressure from the locomotive to said pressure-responsive member, a source of compressed air supply, a controlling cock, 80 and means for connecting said cock with said steam conducting means, said air supply and the casing inlet.
50. 14. In a locomotive, the combination with an exhaust passage, a valve for said passage, a source of pressure-fluid supply and a source of steam supply, pressure-fluid-actuated means for actuating said valve including controlling mechanism comprising a device operable to control the flow of air 90 therethrough either to or from said valve.
55. 15. In a locomotive having an exhaust passage, the combination of valve mechanism for said passage adapted normally to close the passage but free to operate in the direction of exhaust pressure to permit the escape of the latter, pressure-fluid actuated means for moving said valve mechanism into open position, and a valve operable automatically when the locomotive is operating 100 under steam pressure to govern the flow of pressure fluid to the last mentioned means.
60. 16. In a locomotive the combination with a cylinder and an exhaust passage, of a valve for said passage freely movable in the direction of exhaust steam, pressure fluid actuated means for moving said valve into open position, and means responsive to the pressure of steam admitted to said cylinder for controlling the flow of pressure fluid to 110 the first mentioned means.
65. 17. The combination with a locomotive cylinder and exhaust passage leading therefrom, of a valve for controlling said passage, pressure fluid actuated means for moving said valve into open position, and valve mechanism for controlling the flow of pressure fluid to the last mentioned means, said mechanism comprising a casing having an inlet connected with a source of pressure 120 fluid supply and an outlet connected with said pressure fluid actuated means, a valve member normally preventing the flow of pressure fluid through the casing, and means connected with the locomotive cylinder and 125
70. 18. In a locomotive, the combination with an exhaust passage, a valve for said passage, a source of pressure fluid supply and a source of steam supply, pressure fluid actuated means for moving said valve into open position, and valve mechanism for controlling the flow of pressure fluid to the last mentioned means, said mechanism comprising a casing having an inlet connected with a source of pressure 130 fluid supply and an outlet connected with said pressure fluid actuated means, a valve member normally preventing the flow of pressure fluid through the casing, and means connected with the locomotive cylinder and 135

responsive to steam pressure therein for operating said valve member whereby to permit the flow of pressure fluid through the casing.

5 18. In a locomotive, the combination with an exhaust passage and a valve for completely closing said passage, of pressure-fluid-actuated means for actuating said valve to permit of the passage of exhaust steam there- 70
10 through, said means including a controlling device embodying a valve for controlling the flow of pressure-fluid, and means for operating said valve comprising a pressure- 75
15 responsive member, and means for conducting steam admitted to the locomotive for operating the same to said pressure-responsive member for automatically actuating said valve when a locomotive is under load.

19. In a locomotive, the combination with an exhaust passage and a valve therefor, of pressure-fluid-actuated mechanism including a casing having an inlet port communicating with a source of pressure-fluid supply, an outlet port connected with said valve, 80
25 valve means for controlling the flow of pressure-fluid from said inlet to said outlet, a pressure-responsive member in said casing adapted to actuate said valve means, means for conducting pressure-fluid to said valve 85
30 means, a source of pressure-fluid supply and means for controlling the flow of pressure-fluid to said casing inlet and to said conducting means.

20. In a locomotive, the combination of an exhaust passage, a valve operable to close said passage, and means for actuating said valve into open position comprising in combination with a source of pressure-fluid supply, means for conducting pressure-fluid to the valve, and a device for controlling the flow of pressure-fluid through said conducting means comprising a casing having a substantially central bore, a chamber at one end of said bore provided with an inlet, 90
35 said bore having an outlet, a valve member operable in said casing and having a head adapted to seat at the upper end of the bore, spring means for maintaining said head upon its seat, a longitudinal and a circumferential groove in the periphery of said valve member intercommunicating with each other, a chamber in the casing having an exhaust 95
40 port and communicating with one end of said longitudinal groove in the valve member, and means for operating said valve member whereby to establish communication either between said inlet and said outlet or between said outlet and said exhaust port, the last mentioned means comprising a pressure-responsive member, and means for conducting to said member a supply of steam admitted to the locomotive for operating the 100
45 same,

21. In a locomotive, the combination of an exhaust passage, a valve operable to close said passage, and means for actuating said valve into open position comprising, in combination with a source of pressure-fluid supply, means for conducting pressure-fluid to the valve, and a device for controlling 105
50 the flow of pressure-fluid through said conducting means comprising a casing having a substantially central bore, a chamber at one end of said bore provided with an inlet, said bore having an outlet, a valve member operable in said casing and having a head adapted to seat at one end of the bore, spring means for maintaining said head upon its seat, a longitudinal and a circumferential groove in the periphery of said valve member intercommunicating with each other, a chamber in the casing having an exhaust 110
55 port and communicating with one end of said longitudinal groove in the valve member, and means for operating said valve member whereby to establish communication either between said inlet and said outlet or between said outlet and said exhaust port, the last mentioned means comprising a pressure-responsive member, and means for conducting to said member a supply of steam admitted to the locomotive for operating the 115
60 same,

22. In combination with a passage having a valve adapted to completely close the same and operable into position to provide an opening through the passage, pressure-fluid-actuated means for actuating the valve including a device embodying valve means for controlling the flow of pressure-fluid therethrough, pressure-fluid-actuated means for actuating said valve means, and a cock operable to control the flow of pressure-fluid to said device and to the actuating means for the valve means of said device.

23. In a locomotive, the combination with a valve to be operated by pressure-fluid, a 120
65

the flow of pressure-fluid through said conducting means comprising a casing having a substantially central bore, a chamber at one end of said bore provided with an inlet, said bore having an outlet, a valve member operable in said casing and having a head adapted to seat at one end of the bore, spring means for maintaining said head upon its seat, a longitudinal and a circumferential groove in the periphery of said valve member intercommunicating with each other, a chamber in the casing having an exhaust port and communicating with one end of said longitudinal groove in the valve member, and means for operating said valve member whereby to establish communication either between said inlet and said outlet, or between said outlet and said exhaust port, the last mentioned means comprising a pressure-responsive member and means for conducting pressure-fluid to said member.

24. In a locomotive, the combination of an exhaust passage, a valve operable to close said passage, and means for actuating said valve into open position comprising in combination with a source of pressure-fluid supply, means for conducting pressure-fluid to the valve, and a device for controlling the flow of pressure-fluid through said conducting means comprising a casing having a substantially central bore, a chamber at one end of said bore provided with an inlet, said bore having an outlet, a valve member operable in said casing and having a head adapted to seat at the upper end of the bore, spring means for maintaining said head upon its seat, a longitudinal and a circumferential groove in the periphery of said valve member intercommunicating with each other, a chamber in the casing having an exhaust port and communicating with one end of said longitudinal groove in the valve member, and means for operating said valve member whereby to establish communication either between said inlet and said outlet or between said outlet and said exhaust port, the last mentioned means comprising a pressure-responsive member, and means for conducting to said member a supply of steam admitted to the locomotive for operating the same,

25. In a locomotive, the combination with a valve to be operated by pressure-fluid, a 125
65

source of pressure-fluid supply, a source of steam supply, means for conducting pressure-fluid to the valve to be operated having a controlling device provided with valve 5 means for controlling the flow of pressure-fluid through said conducting means, and means for conducting to said device steam admitted to the locomotive for operating the same whereby to actuate the valve means 10 thereof.

25. The combination with a locomotive cylinder and exhaust passage leading therefrom, of valve means for controlling said passage, pressure-fluid-actuated means for 15 operating said valve, and mechanism for automatically controlling the flow of pressure fluid to the valve means, the operation of said mechanism being dependent upon the pressure of the steam admitted to said 20 cylinder.

26. The combination with a locomotive exhaust passage of a valve member adapted to close said passage, pressure-fluid-actuated means for actuating said valve including a 25 chamber having a piston therein, means for conducting pressure-fluid to said chamber, a device for controlling the flow of pressure-fluid through said conducting means, said device having a pressure-fluid-actuated 30 valve member therein, and a single controlling valve for governing the flow of pressure-fluid to said device to actuate it and through it for passage to said chamber.

35. The combination with a locomotive exhaust passage, of a valve member adapted to close said passage, pressure-fluid-actuated means for actuating said valve including a chamber having a piston therein, means for conducting pressure-fluid to said chamber, a 40 device for controlling the flow of pressure-fluid through said conducting means, said device having a pressure-fluid-actuated valve member therein, and a single controlling valve for governing the flow of pressure-fluid to said valve member and to said 45 device for passage therethrough to said chamber and from said chamber back to said device for exhaust.

50. A locomotive exhaust nozzle having an annular horizontally disposed seat, a valve member guided for up and down movement in said nozzle and adapted to engage with said seat to completely close the passage through the nozzle, a chamber in 55 said valve member, a tubular stem having rigid therewith a piston operable in said chamber, and means for conducting pressure-fluid to the upper end of said chamber whereby to assist the exhaust steam passing through the nozzle to lift said valve member, said means having a controlling valve therein operable automatically upon the admission of steam to the locomotive 60 for operating the same.

65. A locomotive exhaust nozzle having

an annular horizontally disposed seat, a valve member guided for up and down movement in said nozzle and adapted to engage with said seat to completely close the 70 passage through the nozzle, a chamber in said valve member, a tubular stem having rigid therewith a piston operable in said chamber, and means for conducting pressure-fluid to the upper end of said chamber whereby to assist the exhaust steam passing 75 through the nozzle to lift said valve member, said conducting means having controlling mechanism operable automatically by steam pressure supplied to the locomotive 80 for operating the same.

30. A locomotive exhaust nozzle having an annular horizontally disposed seat, a valve member guided for up and down movement in said nozzle and adapted to engage with said seat to completely close the 85 passage through the nozzle, a chamber in said valve member, a tubular stem having rigid therewith a piston operable in said chamber, and means for conducting pressure-fluid to the upper end of said chamber whereby to assist the exhaust steam passing 90 through the nozzle to lift said valve member, said conducting means having a controlling device interposed therein provided with a valve member, a pressure-responsive member for actuating said valve member, means for conducting pressure-fluid to said pressure-responsive member, and a single valve 95 for governing the flow of pressure-fluid to said pressure-responsive member and to said device for the passage to said chamber in the exhaust valve.

31. The combination with a locomotive exhaust passage and a valve therefor, pressure-fluid-actuated means for operating said valve, and means for conducting pressure-fluid to said first mentioned means including a casing having a controlling valve member therein, said casing comprising two sections detachably connected together and providing a chamber, a pressure-responsive member in said chamber adapted to actuate said valve member, and means for conducting pressure-fluid to said pressure-responsive member.

32. In a locomotive, the combination with a cylinder, an exhaust passage, a valve adapted to completely close said passage, pressure-fluid actuated means for actuating said valve, an air reservoir, means for conducting air from said reservoir to said valve-actuating means, means for connecting said conducting means with said cylinder, and a single valve for controlling the flow of pressure-fluid to said valve actuating means and from said cylinder to the air reservoir when the cylinder and its piston are converted into a pump.

33. The combination with an exhaust passage and a valve therefor, of actuating 130

means for said valve operable by pressure-fluid, means for conducting pressure-fluid to said valve-actuating means, a device for controlling the flow of pressure-fluid through 5 the conducting means comprising a casing having a valve therein, a pressure-responsive member also located within said casing and operatively associated with said valve member, means for conducting to said pressure- 10 responsive member a supply of steam admitted to the engine for operating the latter, and means establishing communication between said steam-conducting means and said air-conducting means including a single 15 valve operable to control communication between said two conducting means and through the air conducting means.

34. A locomotive exhaust nozzle having a controlling valve therefor, pressure-fluid-actuated means for operating said valve, a source of air supply, means for conducting air under pressure to said valve-actuating means comprising a device having a controlling valve and a pressure-responsive member 20 for actuating said valve, and means for conducting a supply of air from said air-conductor to said pressure-responsive member.

35. In a locomotive, the combination with 30 an exhaust passage having a controlling valve, pressure-fluid-actuated means for actuating said valve, means for conducting a supply of compressed air to said actuating means including a controlling device comprising a casing having a valve therein and 35 an exhaust port, said valve being adapted to control the flow of air therethrough to said actuating means and from said actuating means to said exhaust port, a pressure-responsive member operatively associated with 40 said valve member, and means for conducting a supply of air from said conducting means to said pressure-responsive member.

36. In a locomotive, the combination with 45 an exhaust passage, a valve for said passage, means operable by pressure-fluid to actuate said valve, means for conducting pressure-fluid to said valve-actuating means including a controlling device comprising a 50 casing having a valve member therein, a pressure-responsive member for actuating

said valve member, means for admitting to said pressure-responsive member a supply of steam under pressure supplied to the locomotive for operating the latter, said casing 55 having an inlet and an outlet communication between which is controlled by said valve member, and means for conducting steam under pressure from the casing to said inlet.

37. In a locomotive having an exhaust passage, valve means for controlling said passage, pressure-fluid-actuated means for operating said valve means, and means operable automatically by steam pressure admitted to the engine to operate the same whereby to control the flow of pressure fluid to the last mentioned means.

38. In a locomotive, an exhaust passage, 70 a valve for said passage, and pressure-fluid-actuated means for actuating said valve including a pressure-responsive member, and means for conducting exhaust steam from the exhaust passage below said valve to said member.

39. In a locomotive having an exhaust passage, the combination of a valve for closing said passage, a source of air supply under pressure, pressure-fluid-actuated means for moving said valve into open position, 80 and a device for controlling the flow of air from said source of supply to said means, said device being operable automatically by steam pressure admitted to the engine to operate the same.

40. In a locomotive having an exhaust passage, the combination of a valve for said passage, separate sources of air and steam supply under pressure, pressure-fluid-actuated means for moving said valve into open 90 position, and a device for controlling the flow of pressure fluid to said means, said device being connected with said source of air supply and also with the source of steam supply and including a manually operable valve whereby the flow of either air or steam to the engine to actuate it may be selectively controlled at the will of the operator.

In testimony whereof, I have hereunto set my hand.

JOHN E. OSMER.
